UNITED STATES PATENT OFFICE.

JOACHIM JUNGWIRTH, OF DETROIT, MICHIGAN, ASSIGNOR TO WALTER F. STIMPSON, OF SAME PLACE.

DESIGN FOR A SCALE-FRAME.

SPECIFICATION forming part of Design No. 32,334, dated March 13, 1900.

Application filed February 9, 1900. Serial No. 4,696. Term of patent 14 years.

To all whom it may concern:

Be it known that I, JOACHIM JUNGWIRTH, a citizen of the United States, residing at Detroit, in the county of Wayne and State of Michigan, have invented a certain new and original Design for a Scale-Frame, of which the following is a specification, reference being had therein to the accompanying drawings, in which—

Figure 1 is a front elevation of my scale-frame. Fig. 2 is a side elevation thereof. A is a flat substantially-rectangular base. B is a horizontal shelf or cap arranged over one end of said base. C are supports connecting said cap with the opposite corners of the base. These supports have the appearance of stems and are of a substantially-ogee curve, the lower ends being turned inward

and rounded at a. The upper ends have a slightly-enlarged rounded portion b, while intermediate the ends on the inner edge is the projection c.

The leading feature of my design is the configuration of the supports connecting the cap and base and being of a substantially-ogee curve and having the inwardly-extending rounded lower ends x.

What I claim as my invention is—

The design for a scale-frame, substantially as herein shown and described.

In testimony whereof I affix my signature in presence of two witnesses.

JOACHIM JUNGWIRTH.

Witnesses:

M. B. O'DOGHERTY,
H. C. SMITH.
